UNITED STATES PATENT OFFICE.

GEORGE LAWSON ROBERTSON, OF PHILADELPHIA, PENNSYLVANIA.

PNEUMATIC HAMMER.

1,107,550.

Specification of Letters Patent. Patented Aug. 18, 1914.

Application filed April 15, 1914. Serial No. 832,020.

To all whom it may concern:

Be it known that I, GEORGE LAWSON ROBERTSON, a citizen of the United States, residing at Philadelphia, in the county of Philadelphia and State of Pennsylvania, have invented certain new and useful Improvements in Pneumatic Hammers, of which the following is a specification.

My invention relates to improvements in pneumatic hammers, an object of the invention being to provide a pneumatic hammer with an improved construction of valve coöperating with an improved arrangement of ports and passages in the hammer 10 to control the movement of the piston.

A further object is to provide in the barrel, a longitudinally movable shank-supporting bushing, the movement of which, by pressure of the tool against a rivet, automatically admits fluid to the hammer, and when pressure on the tool is relieved, the bushing is caused to move to stop the operation of the hammer.

A further object is to provide an improved pneumatic hammer in which accidental displacement of the working tool and piston is prevented.

A further object is to provide a pneumatic hammer in which the ordinary throttle valve in the handle is dispensed with, and which is caused to operate, and to cease operation in accordance with the pressure of the tool in the barrel against a rivet or other object.

A further object is to provide an improved two-part valve, both parts movable and moved by fluid pressure to control the passage of fluid, so that the operation is entirely automatic.

With these and other objects in view, the invention consists in certain novel features of construction and combinations and arrangements of parts, as will be more fully hereinafter described and pointed out in the 40 claims.

In the accompanying drawings: Figure 1 is a view in longitudinal section illustrating my improvements in normal operative position with the piston moving forwardly.

Fig. 2 is an enlarged view in side elevation of the inner valve section. Fig. 3 is a similar view of the outer valve section. Fig. 4 is a fragmentary view in longitudinal section on an enlarged scale showing the position of the valve during the return stroke

of the piston. Fig. 5 is a view in cross section on the line 5—5 of Fig. 4. Fig. 6 is a view in cross section on the line 6—6 of Fig. 4. Fig. 7 is a view similar to Fig. 1 showing the hammer in its inoperative position. Fig. 8 is a view in cross section on the line 8—8 of Fig. 4, and Fig. 9 is a fragmentary end elevation of the handle socket or cap, illustrating a portion of the locking mechanism for the handle.

1 represents the barrel of my improved pneumatic hammer, having at its rear edge, an enlarged casing 2 in which a valve box 3 is secured. This valve box is, for convenience of manufacture, formed of a plurality of sections having fixed relationship to each other and secured together in any approved manner.

I have illustrated dowel pins 4 engaging in the barrel to prevent rotary movement of the box. The rear end of the box is closed by a head 5 which has a pin 6 at its periphery engaging in a recess 7 in the casing 2 of barrel 1 to prevent any rotary movement of the head, so that the several 75 ports hereinafter referred to are maintained in alinement. The rear casing end of the barrel is externally screw-threaded as shown at 8 to receive the integral internally screw-threaded cap 9 on the handle 10. To lock 70 this handle against accidental movement, I provide an angular socket 11 in the head 5, which is located in register with a cylindrical socket 12 in the cap 9.

13 is a rod which extends through an opening in the end of the cap, and is provided on its outer end with a disk 14. A nut 15 is fixed to the inner end of the rod 13, and its angular portion is held in the socket 11 by means of a coiled spring 16. 95 The disk 14 has inwardly projecting pins 17 which are normally positioned in sockets 18, and hold the parts against movement. When, however, it is desired to release the handle, this disk is drawn outwardly to 100 draw the pins 17 out of the sockets 18, when the disk can be turned, the pins moving in segmental grooves 19 which hold the disk in a position to contract the spring and hold the locking nut out of engagement with the head. The handle can then be unscrewed and replaced as will be understood.

In the valve box 3, my improved two-part valve is located, and consists of an inner section 20 and an outer section 21, 110

- both of general cylindrical form with the outer section mounted to telescope on the inner section and the inner section located slightly in advance of the outer section as seen clearly in Fig. 4. The inner valve section 20 is provided with four annular flanges 22, 23, 24, and 25, the flanges 24 and 25 being smaller in diameter than the flanges 22 and 23, and said flanges 24 and 25 fitting within the outer valve section 21. It will be noted that the thickness of the wall of valve section 21 is just sufficient to bring the outer surface of said outer section flush with the outer surfaces of flanges 23 and 24.
- It is to be understood that the valve sections are to be made of extremely thin metal, so that they will be relatively light and quickly respond to the action of the pressure fluid, and I have necessarily exaggerated the thickness of metal for clearness of illustration. The outer valve section is provided at its rear end with an annular enlargement 26, and at its extreme rear end has a cylindrical portion 27 which fits a cylindrical block 28 on the head 5, and moves longitudinally of the barrel, but always upon the block for a purpose which will hereinafter appear. The two valve sections have each certain pressure surfaces of different relative areas, and for convenience of description, I shall give each of these pressure surfaces a separate reference character.
- The forward face of the flange 22 constitutes a relatively large pressure surface 29 at the forward end of inner valve section 20. The rear face of flange 25 constitutes a pressure surface 30, slightly smaller than the pressure surface 29. The rear face of the enlargement 26 constitutes a pressure surface 31 which is relatively large as shown. The forward face of the enlargement 26 constitutes a relatively small pressure surface 74, and while both of these surfaces 31 and 74 are on the same enlargement, the difference in the diameter of the forward and rear end of said outer section compensates for the different areas of the pressure surfaces. The other surfaces of the valves are for purposes of cutting off passages and directing the flow of fluid as will be herein-after pointed out.
- In the forward end of the barrel 1, I provide a longitudinally movable bushing 32 to receive the shank 33 of the tool 34, an ordinary guard 35 being illustrated to hold the tool in the barrel. The bushing 32 is of two external diameters. Its larger diameter, which is at its forward end, is provided with a key 36 which moves in a longitudinal groove 37 in the inner face of the barrel so as to limit the movement of the bushing. To position the key in this groove, the barrel is provided with an internal annular groove 38 which communicates with a groove
- 39, extending to the end of the barrel so that the bushing can be inserted with the key in groove 39 until the annular groove 38 is reached. The bushing is then given a partial rotary movement until the key registers with groove 36, when the bushing can be moved within the confines of the groove without danger of falling out of the barrel.
- The barrel is formed with an annular recess 40, which accommodates the larger diameter of the bushing, and in the inner end of this recess, I locate a coiled spring 41 which bears against a shoulder 42 on the bushing and tends always to press the bushing in a forward direction, it being understood that the smaller diameter of the bushing fits within the bore 43 of the barrel, and holds the shank 33 of the tool in position to be engaged by the reciprocating piston 44. The handle 10 is provided with an inlet passage 45 for the motive fluid which enters an annular chamber 46 in the cap 9 and then flows through a circular series of longitudinal passages 47, there being ten of these passages 47 illustrated. I would have it understood that I do not limit myself to the number of these or other passages hereinafter referred to, but in order that I may set forth an arrangement which I believe to be a preferable one, I shall define the number of such passages which are stated proportionately rather than with a view to any definiteness of number.
- Assuming the parts to be in normal working position, with the piston moving forwardly as shown in Fig. 1, the passages 47 communicate with radial ports 48 in the enlargement 26 of outer valve section 21. These ports 48 register with an annular groove 49 in the valve box 3, said groove being located approximately midway between the ends of the passages 47, hence when in the position stated, the live fluid has free access to the interior of the valve section 21, and it will be noted that said valve section, where it is provided with the ports 48, has an internal annular groove 50 for the better distribution of live fluid entering the same. When in this position, the inner valve section 20 is located in its extreme forward position, so that its rear end registers with the forward wall of groove 50, and the live fluid flows through the valve section 20 and exerts pressure against the rear end of piston 44 driving the latter forwardly. The fluid in advance of the piston is forced out through a series of longitudinal passages 51, preferably five, which communicate at their rear end, with exhaust passages 52 which discharge forwardly and against a protecting ring 53 as shown. When the piston 44 almost reaches the shank 33 of the tool, it will uncover the end of a passage 54 which directs the live fluid against the forward pressure surface 29 of inner valve section 20.

Immediately the inner valve section is caused to move rearwardly and assumes the position shown in Fig. 4. The blow of the piston against the tool shank, causes a rebound of the piston which is almost sufficient to return it to the rear of the barrel, and hence very little fluid is necessary to cause this return. During the return movement of the piston, the live fluid in passages 47 flows through the forward ends of said passages into an annular chamber 55, and thence through openings 56 and 57 in the outer valve section, the fluid in its passage being directed from one opening to the other by reason of the fact that an annular chamber 58 is formed between the flanges 24 and 25 of the inner valve section. The openings 57 communicate with an internal annular groove 59 in the valve box 3, and said groove communicates with the rear ends of the passages 51, so that while a portion of this live fluid will escape through the exhaust passages 52, a sufficient amount will flow forwardly through the passages 51 to insure a complete return of the piston to the rear end of the barrel. The fluid in front of the piston exhausts freely through a circular series of openings 60 in the inner valve section 20 into an internal annular groove 61 in the valve box, the latter being provided with a series of exhaust ports 62. The groove 61 also communicates by radial passages 63 with the exhaust ports 52, so that there is a free exhaust during the return movement of the piston. During the rearward movement of the piston, this fluid in front of the piston exerts a pressure through passage 54 against the pressure surface 29 until such passage is closed by the piston. To supply pressure on this surface, during the rest of the rearward movement of the piston, sufficient to prevent the valve from accidentally shifting, I provide a radial port 64 in a longitudinal passage 65. The passage 65 communicates at its rear end with the annular chamber 46, so that it is always supplied with live fluid. The radial port 64 communicates with an annular groove 66 in the box 3, so that a sufficient amount of live fluid is admitted against the pressure surface 29 when the section 20 is in its rearward position. When, however, the section 20 is in its forward position, this groove 66 is cut off by the flange 22. The inner valve section, near its rear end, is provided with a circular series of openings 67 which communicate with a space 68 formed between the rear pressure surface 30 of the inner valve section, and an annular surface 69 on the outer valve section. This pressure surface 30 is slightly smaller than the pressure surface 29, and the movement of the pressure fluid in front of the piston is not sufficient to shift the valve until the piston reaches the extreme of its rearward movement. It will be noted that

the inner valve section 20 is of slightly greater internal diameter from a point 70 to its rear end. This is shown on an exaggerated scale on the drawing. It is extremely slight in actual construction. The purpose of this is to overcome a severe fluid pocket between the piston 44 and the head 5, but the rearward movement of the piston will create a sufficient pressure to overcome the pressure on surface 39 and exert a greater pressure on surface 30 to cause the valve section 20 to move forwardly to its position above described. The access of pressure between the piston and the head will be enough to accomplish this purpose, but to prevent any possibility of too great a pressure, and hence a shortening of the movement of the piston, the difference in internal diameter is provided, such excessive fluid escaping through the openings 60 into the exhaust passages.

The longitudinal passage 65 above referred to extends to the forward end of the barrel, where it is normally cut off by the larger diameter of the bushing as shown clearly in Fig. 1. When, however, the bushing is moved forwardly by the action of spring 41, after the pressure on the tool is relieved, the air in this passage 65 will flow around the recess 40 and into a longitudinal passage 71 which extends to the rear of the barrel and exerts pressure against the pressure surface 31 of the outer valve section 21, causing this outer valve section to move forwardly to the position shown in Fig. 7, and when in such position, entirely cut off the inlet of live fluid to the hammer. When the bushing is moved rearwardly by reason of a pressure of the tool against a rivet, the flow of fluid through passage 65 will be cut off and the end of passage 71 will be connected with the groove 39 in the barrel by means of a longitudinal groove 72 in the outside of the bushing, so that the pressure surface 31 is exposed to the atmosphere, and does not resist the movement of the valve section. As soon as this takes place, the pressure of live fluid from the forward ends of the passages 47 against the extremely small pressure surface 74, at the forward portion of the enlargement 26 of outer valve section 21, compels the outer valve section to move rearwardly so as to admit fluid to the hammer and permit the operation as above described.

The operation is as follows: Fig. 7 shows the hammer in its locked inoperative position in which it will be observed that the live fluid in passage 65 assists the spring 41 in exerting a pressure on the shoulder 42 to maintain the bushing in its forward position, and as above explained when in this position, the live fluid passes through passage 71, and exerts pressure upon the surface 31 to cut off the entrance of live

fluid to the other parts of the hammer. When the tool 34 is pressed against a rivet, the bushing 32 will be moved rearwardly. The first operation of this rearward movement will be to cut off passage 65, so that it is only necessary to overcome the pressure of the spring to hold the device in operative position. Furthermore, this rearward movement of the bushing opens the outlet end of passage 71 at the forward end of the hammer, so that there is no pressure now against the surface 31. Instantly, the live fluid in the passage 47 exerts a rearward pressure against surface 74, causing the outer section 21 to move rearwardly, and hence the several ports and passages will be in communication as shown in Fig. 1. It is not necessary to again describe the flow of fluid in its movement of the piston, except to say that the operation of shifting the valve is entirely automatic, and during the normal operation, the outer section 21 remains stationary, while the inner section 20 is moved longitudinally. The forward movement of the inner section 21 is limited by the engagement of surface 29 with the valve box 3, and the rearward movement of this inner section is limited by the flange 23 engaging the forward end of outer section 21. The outer section moves only to cut off the supply of air to the working parts of the hammer as above set forth. The rearward movement of this outer section is limited by the engagement of the rear end of the valve section with the head 5 and the forward movement by the engagement of the forward end of the outer section with the flange 23.

It will be noted that my improvements prevent accidental removal of the tool or piston. In the event the bushing is forced backward by accident, sufficient to admit motive fluid to the valve, a sharp blow will be delivered against the offending object, but there will be no displacement of the tool. I would also have it understood that the ring 53 and guard 35 are not intended to be complete circles. This permits the guard ring to be turned to direct the exhaust wherever desired, and both parts can be readily inserted in position or removed from the hammer.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In a pneumatic hammer, the combination with a barrel, a valve in one end of the barrel, a longitudinally movable tool-sup-

porting bushing in the other end of the barrel, and said bushing adapted to direct live fluid against the valve to shut off the inlet of fluid to the hammer when the bushing is in its outer position, substantially as described. 70

2. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, and a spring normally pressing said bushing outwardly, substantially as described. 75

3. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, said bushing having an annular shoulder against which live fluid is directed during the outward position of the bushing, substantially as described. 85

4. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, a spring normally pressing said bushing outwardly, said bushing having an annular shoulder against which live fluid is directed during the outward position of the bushing, substantially as described. 90

5. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, said bushing having an annular shoulder against which live fluid is directed during the outward position of the bushing, said fluid pressure against the bushing cut off by the inward movement of the bushing, substantially as described. 105

6. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, a spring normally pressing said bushing outwardly, said bushing having an annular shoulder against which live fluid is directed during the outward position of the bushing, said fluid 120

125

pressure against the bushing being cut off by the inward movement of the bushing, substantially as described.

7. In a pneumatic hammer, the combination with a barrel, a valve in the rear end of the barrel, of a longitudinally movable tool supporting bushing in the forward end of the barrel, a coiled spring around the bushing exerting outward pressure thereon, said barrel having a passage for live fluid exerting outward pressure on the bushing when the latter is in its outward position, said bushing adapted to cut off said live fluid when moved inwardly, and said bushing constructed to direct the live fluid from said passage against the valve to shut off the admission of fluid to the hammer when the bushing is in its outward position, substantially as described.
- 20 8. In a pneumatic hammer, the combination with a barrel, of a reciprocating valve in the rear end of the barrel controlling the movement of the piston, a tool supporting bushing longitudinally movable in the forward end of the barrel, and said bushing constructed to control the flow of fluid to one pressure surface of the valve to move the valve to closed position when the bushing is in its forward position, substantially as described.
- 25 9. In a pneumatic hammer, the combination with a barrel, of a reciprocating valve in the rear end of the barrel controlling the movement of the piston, a tool supporting bushing longitudinally movable in the forward end of the barrel, and said bushing constructed to control the flow of fluid to one pressure surface of the valve to move the valve to closed position when the bushing is in its forward position, and said bushing constructed to expose said pressure surface to the atmosphere when the bushing is moved inwardly by pressure of the tool against the work, substantially as described.
- 30 10. In a pneumatic hammer, the combination with a barrel, of a valve located in the rear end of the barrel, a piston in the barrel, said barrel having passages and ports therein controlled by the valve, whereby the piston is caused to reciprocate in the barrel, a tool-holding bushing movable longitudinally in the forward end of the barrel, said bushing when pressed inwardly adapted to connect passages in the barrel, whereby live fluid pressure is directed against the valve to entirely cut off supply of fluid to the hammer, substantially as described.
- 35 11. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, said valve composed of

two sections, one section reciprocated by the normal inlet of fluid to control the operation of the piston, and the other section movable by the fluid as controlled by the bushing to shut off the flow of fluid when the bushing is in its forward position, substantially as described.

- 70 12. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, a spring normally pressing said bushing outwardly, said valve composed of two sections, one section reciprocated by the normal inlet of fluid to control the operation of the piston, and the other section movable by the fluid as controlled by the bushing to shut off the flow of fluid when the bushing is in its forward position, substantially as described.
- 75 13. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, said bushing having an annular shoulder against which live fluid is directed during the outward position of the bushing, said valve composed of two sections, one section reciprocated by the normal inlet of fluid to control the operation of the piston, and the other section movable by the fluid as controlled by the bushing to shut off the flow of fluid when the bushing is in its forward position, substantially as described.
- 80 14. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, a spring normally pressing said bushing outwardly, said bushing having an annular shoulder against which live fluid is directed during the outward position of the bushing, said valve composed of two sections, one section reciprocated by the normal inlet of fluid to control the operation of the piston, and the other section movable by the fluid as controlled by the bushing to shut off the flow of fluid when the bushing is in its forward position, substantially as described.
- 85 15. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its forward position, substantially as described.

90 16. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, said bushing having an annular shoulder against which live fluid is directed during the outward position of the bushing, said valve composed of two sections, one section reciprocated by the normal inlet of fluid to control the operation of the piston, and the other section movable by the fluid as controlled by the bushing to shut off the flow of fluid when the bushing is in its forward position, substantially as described.

- 95 17. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, a spring normally pressing said bushing outwardly, said bushing having an annular shoulder against which live fluid is directed during the outward position of the bushing, said valve composed of two sections, one section reciprocated by the normal inlet of fluid to control the operation of the piston, and the other section movable by the fluid as controlled by the bushing to shut off the flow of fluid when the bushing is in its forward position, substantially as described.
- 100 18. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its forward position, substantially as described.

125 19. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its forward position, substantially as described.

of fluid to the hammer when the bushing is in its outer position, said bushing having an annular shoulder against which live fluid is directed during the outward position of the bushing, said fluid pressure against the bushing cut off by the inward movement of the bushing, said valve composed of two sections, one section reciprocated by the normal inlet of fluid to control the operation of the piston, and the other section movable by the fluid as controlled by the bushing to shut off the flow of fluid when the bushing is in its forward position, substantially as described.

16. In a pneumatic hammer, the combination with a barrel, a valve in one end of the barrel, a longitudinally movable tool supporting bushing in the other end of the barrel, and said bushing adapted to direct live fluid against the valve to shut off the inlet of fluid to the hammer when the bushing is in its outer position, a spring normally pressing said bushing outwardly, said bushing having an annular shoulder against which live fluid is directed during the outward position of the bushing, said fluid pressure against the bushing cut off by the inward movement of the bushing, said valve composed of two sections, one section reciprocated by the normal inlet of fluid to control the operation of the piston, and the other section movable by the fluid as controlled by the bushing to shut off the flow of fluid when the bushing is in its forward position, substantially as described.

17. In a pneumatic hammer, the combination with a barrel, a valve in the rear end of the barrel, of a longitudinally movable tool supporting bushing in the forward end of the barrel, a coiled spring around the bushing exerting outward pressure thereon, said barrel having a passage for live fluid exerting outward pressure on the bushing when the latter is in its outward position, said bushing adapted to cut off said live fluid when moved inwardly, and said bushing constructed to direct the live fluid from said passage against the valve to shut off the admission of fluid to the hammer when the bushing is in its outward position, said valve composed of two sections, one section reciprocated by the normal inlet of fluid to control the operation of the piston, and the other section movable by the fluid as controlled by the bushing to shut off the flow of fluid when the bushing is in its forward position, substantially as described.

18. In a pneumatic hammer, the combination with a barrel, of a reciprocating valve in the rear end of the barrel controlling the movement of the piston, a tool supporting bushing longitudinally movable in the forward end of the barrel, and said bushing constructed to control the flow of fluid to one pressure surface of the valve to move the valve to closed position when

the bushing is in its forward position, said valve composed of two sections, one section reciprocated by the normal inlet of fluid to control the operation of the piston, and the other section movable by the fluid as controlled by the bushing to shut off the flow of fluid when the bushing is in its forward position, substantially as described.

19. In a pneumatic hammer, the combination with a barrel, of a reciprocating valve in the rear end of the barrel controlling the movement of the piston, a tool supporting bushing longitudinally movable in the forward end of the barrel, and said bushing constructed to control the flow of fluid to one pressure surface of the valve to move the valve to closed position when the bushing is in its forward position, and said bushing constructed to expose said pressure surface to the atmosphere when the bushing is moved inwardly by pressure of the tool against a rivet, said valve composed of two sections, one section reciprocated by the normal inlet of fluid to control the operation of the piston, and the other section movable by the fluid as controlled by the bushing to shut off the flow of fluid when the bushing is in its forward position, substantially as described.

20. In a pneumatic hammer, the combination with a barrel, of a valve located in the rear end of the barrel, a piston in the barrel, said barrel having passages and ports therein controlled by the valve, whereby the piston is caused to reciprocate in the barrel, a tool-holding bushing movable longitudinally in the forward end of the barrel, said bushing when pressed inwardly adapted to connect passages in the barrel, whereby live fluid pressure is directed against the valve to entirely cut off supply of fluid to the hammer, said valve composed of two sections, one section reciprocated by the normal inlet of fluid to control the operation of the piston, and the other section movable by the fluid as controlled by the bushing to shut off the flow of fluid when the bushing is in its forward position, substantially as described.

21. In a pneumatic hammer, the combination with a barrel, a valve in one end of the barrel, a longitudinally movable tool supporting bushing in the other end of the barrel, and said bushing adapted to direct live fluid against the valve to shut off the inlet of fluid to the hammer when the bushing is in its outer position, said valve composed of two cylindrical telescoping sections, the outer section movable longitudinally to shut off fluid to the inner section, said movement controlled by the bushing, and the inner section movable longitudinally by the fluid to control the movement of the piston, substantially as described.

22. In a pneumatic hammer, the combina-

- tion with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, a spring normally pressing said bushing outwardly, said valve composed of two cylindrical telescoping sections, the outer section movable longitudinally to shut off fluid to the inner section, said movement controlled by the bushing, and the inner section movable longitudinally by the fluid to control the movement of the piston, substantially as described.
23. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, said bushing having an annular shoulder against which live fluid is directed during the outward position of the bushing, said valve composed of two cylindrical telescoping sections, the outer section movable longitudinally to shut off fluid to the inner section, said movement controlled by the bushing, and the inner section movable longitudinally by the fluid to control the movement of the piston, substantially as described.
24. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, a spring normally pressing said bushing outwardly, said bushing having an annular shoulder against which live fluid is directed during the outward position of the bushing, said valve composed of two cylindrical telescoping sections, the outer section movable longitudinally to shut off fluid to the inner section, said movement controlled by the bushing, and the inner section movable longitudinally by the fluid to control the movement of the piston, substantially as described.
25. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, said bushing having an annular shoulder against which live fluid is directed during the outward position of the bushing, said valve composed of two cylindrical telescoping sections, the outer section movable longitudinally to shut off fluid to the inner section, said movement controlled by the bushing, and the inner section movable longitudinally by the fluid to control the movement of the piston, substantially as described.
26. In a pneumatic hammer, the combination with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, a spring normally pressing said bushing outwardly, said bushing having an annular shoulder against which live fluid is directed during the outward position of the bushing, said fluid pressure against the bushing cut off by the inward movement of the bushing, said valve composed of two cylindrical telescoping sections, the outer section movable longitudinally to shut off fluid to the inner section, said movement controlled by the bushing, and the inner section movable longitudinally by the fluid to control the movement of the piston, substantially as described.
27. In a pneumatic hammer, the combination with a barrel, a valve in the rear end of the barrel, of a longitudinally movable tool supporting bushing in the forward end of the barrel, a coiled spring around the bushing exerting outward pressure thereon, said barrel having a passage for live fluid exerting outward pressure on the bushing when the latter is in its outward position, said bushing adapted to cut off said live fluid when moved inwardly, and said bushing constructed to direct the live fluid from said passage against the valve to shut off the admission of fluid to the hammer when the bushing is in its outward position, said valve composed of two cylindrical telescoping sections, the outer section movable longitudinally to shut off fluid to the inner section, said movement controlled by the bushing, and the inner section movable longitudinally by the fluid to control the movement of the piston, substantially as described.
28. In a pneumatic hammer, the combination with a barrel, of a reciprocating valve in the rear end of the barrel controlling the movement of the piston, a tool supporting bushing longitudinally movable in the forward end of the barrel, and said bushing constructed to control the flow of fluid to one pressure surface of the valve to move the valve to closed position when the bushing is in its forward position, said valve composed of two cylindrical telescoping sections, the outer section movable longitudinally to shut off fluid to the inner section, said movement controlled by the bushing, and the inner sec-

tion movable longitudinally by the fluid to control the movement of the piston, substantially as described.

29. In a pneumatic hammer, the combination with a barrel, of a reciprocating valve in the rear end of the barrel controlling the movement of the piston, a tool supporting bushing longitudinally movable in the forward end of the barrel, and said bushing constructed to control the flow of fluid to one pressure surface of the valve to move the valve to closed position when the bushing is in its forward position, and said bushing constructed to expose said pressure surface to the atmosphere when the bushing is moved inwardly by pressure of the tool against a rivet, said valve composed of two cylindrical telescoping sections, the outer section movable longitudinally to shut off fluid to the inner section, said movement controlled by the bushing, and the inner section movable longitudinally by the fluid to control the movement of the piston, substantially as described.
30. In a pneumatic hammer, the combination with a barrel, of a valve located in the rear end of the barrel, a piston in the barrel, said barrel having passages and ports therein controlled by the valve, whereby the piston is caused to reciprocate in the barrel, a tool-holding bushing movable longitudinally in the forward end of the barrel, said bushing when pressed inwardly adapted to connect passages in the barrel, whereby live fluid pressure is directed against the valve to entirely cut off supply of fluid to the hammer, said valve composed of two cylindrical telescoping sections, the outer section movable longitudinally to shut off fluid to the inner section, said movement controlled by the bushing, and the inner section movable longitudinally by the fluid to control the movement of the piston, substantially as described.
31. In a pneumatic hammer, the combina-

tion with a barrel, a valve in one end of the barrel, a longitudinally movable tool-supporting bushing in the other end of the barrel, and said bushing adapted to direct live fluid against the valve to shut off the inlet of fluid to the hammer when the bushing is in its outer position, said barrel having an internal longitudinal groove communicating at one end with an internal annular groove, the latter having a longitudinal entrance groove, and said bushing having a key adapted to enter through the last-mentioned groove, turned in the annular groove, and positioned in the longitudinal groove, whereby the movement of the bushing is limited in both directions, substantially as described.

32. In a pneumatic hammer, the combination with a barrel, a valve in one end of the barrel, a longitudinally movable tool-supporting bushing in the other end of the barrel, said bushing adapted to direct live fluid against the valve to shut off the inlet of fluid to the hammer when the bushing is in its outer position, and means exerting a continuous outward pressure on the bushing, substantially as described.

33. In a pneumatic hammer, the combination with a barrel, a valve in one end of the barrel, a longitudinally movable tool-supporting bushing in the other end of the barrel, said bushing adapted to direct live fluid against the valve to shut off the inlet of fluid to the hammer when the bushing is in its outer position, and a coiled spring around the outside of the bushing exerting a continuous outward pressure on the bushing, substantially as described.

In testimony whereof I have signed my name to this specification in the presence of two subscribing witnesses.

GEORGE LAWSON ROBERTSON.

Witnesses:

M. E. DITTUS,
CHAS. E. POTTS.

It is hereby certified that in Letters Patent No. 1,107,550, granted August 18, 1914, for an improvement in "Pneumatic Hammers," an error appears in the printed specification requiring correction as follows: Page 5, line 53, for the word "inwardly" read *forwardly*; and that the said Letters Patent should be read with this correction therein that the same may conform to the record of the case in the Patent Office.

Signed and sealed this 22nd day of September, A. D., 1914.

[SEAL.]

R. F. WHITEHEAD,
Acting Commissioner of Patents.
